UNITED STATES PATENT OFFICE.

GUSTAVE A. HENCKEL, OF NEW YORK, N. Y., ASSIGNOR TO HENCKEL & ELCOX.

DESIGN FOR A RING.

SPECIFICATION forming part of Design No. 33,607, dated November 20, 1900.

Application filed August 24, 1900. Serial No. 27,962. Term of patent 7 years.

to all whom it may concern:

Be it known that I, GUSTAVE A. HENCKEL, a citizen of the United States, residing in the borough of Manhattan, city, county, and State 5 of New York, have invented and produced a new and original Design for Rings, of which the following is a specification.

My design relates to rings, and especially to that class of rings known as "teething rings." I will describe a ring embodying my invention.

In the accompanying drawings, Figure 1 is a front or face view of a ring embodying my invention. Fig. 2 is a transverse sectional 5 view.

Similar letters of reference designate corresponding parts in both of the figures.

A represents a ring-shaped body, which is here shown as being of considerable width.

o The leading or essential feature of my design consists in the portrayal on a face of the ring a

character found in nursery-rhymes, nursery-tales, &c. For example, the character here portrayed is that of "Little Jack Horner." The figure is located on one portion of the face 25 of the ring. The inner periphery of the ring at that portion of the ring-body on which the figure is portrayed is irregular, as indicated by a. The irregularity is made to conform to the outline of a portion of the figure. 30

Having described my invention, what I claim is—

The design for a ring as shown and described.

In testimony whereof I have signed my 35 name to this specification in the presence of two subscribing witnesses.

GUSTAVE A. HENCKEL.
